FIG. 1

FIG. 2

FIG. 3

INVENTOR

Lewis J. Doolittle

UNITED STATES PATENT OFFICE.

LEWIS J. DOOLITTLE, OF SOUTH ORANGE TOWNSHIP, ESSEX COUNTY, NEW JERSEY,
ASSIGNOR TO PYRENE MANUFACTURING COMPANY, A CORPORATION OF DELA-
WARE.

PORTABLE FIRE-EXTINGUISHER.

1,185,294.

Specification of Letters Patent. Patented May 30, 1916.

Application filed November 18, 1913. Serial No. 801,671.

To all whom it may concern:

Be it known that I, LEWIS J. DOOLITTLE, a citizen of the United States, and resident of the township of South Orange, county of Essex, and State of New Jersey, have invented certain new and useful Improvements in Portable Fire-Extinguishers, of which the following is a specification.

This invention relates to a portable fire extinguisher of the type wherein a gas is generated by chemical action when the device is in use and the gas pressure utilized to force out a fire extinguishing liquid.

The object of the invention is to provide a fire extinguisher of the class described wherein the gas is generated in a large volume in a short period of time, whereby the extinguisher is rendered operative at the earliest possible moment and a positive and efficient operation of the same assured.

In carrying out the invention a suitable container is provided for the fire extinguishing liquid. A small container filled with an acid and a receptacle containing a salt are relatively positioned so that the acid when liberated is caused to immediately flow over and act upon a large amount of the salt simultaneously, thus causing a large volume of gas to be generated in a very short period of time. The gas pressure so generated is caused to enter the container in which the fire extinguishing liquid is contained, the pressure thereupon forcing the same through a suitable pipe, by means of which it is directed upon the fire.

The peculiar and novel features of construction of a fire extinguisher embodying this invention will be described more fully hereinafter in connection with the description of the same as illustrated in the accompanying drawings.

In the drawings like parts in the several views have been given the same reference numerals.

Figure 1 is a sectional side elevation of a portable fire extinguisher embodying the invention. Fig. 2 is a sectional view of a portion of Fig. 1, showing the parts in their operating position. Fig. 3 is a sectional plan view on the line 3—3 of Fig. 1.

The container 1 for the fire extinguishing liquid may be of any suitable shape, usually cylindrical in form and provided with a carrying handle 2 at its upper end. An operating handle 3 is attached to a stem 4 ex-

tending through a suitable packing to the interior of the upper portion of the container 1. The lower end of the stem 4 is attached to a supporting frame 5 in which the acid container 6 is carried.

The acid container 6 is provided with a double bottom formed by the walls 7 and 8 dividing the same into two sections, both of which are filled with an acid. A knife edge or other suitable puncturing device 9 is mounted upon the lower portion of the frame 5 and the acid container 6 normally rests upon the same, as shown in Fig. 1.

One or more sharp pointed pins, such as 10, are mounted in the upper portion of the container 1 so as to project downwardly through openings in the frame 5, thus forming a guide for the same, and having their lower or pointed ends adjacent to the upper end of the acid container 6. These pins 10 are provided with a shoulder adjacent the lower ends thereof, the purpose of which will be explained more fully hereinafter.

A gas generating chamber 11, preferably cylindrical in form and closed at both ends, is suspended in the container 1, as shown in Fig. 1, and is provided with a valve 12 at the upper end thereof which is arranged to permit the gas generated therein to pass out to the interior of the container 1, where it exerts a pressure upon the fire extinguishing liquid contained therein and forces the same out through the vertical tube 13 and flexible tube 14, which is provided with a nozzle 15 by means of which the fluid is directed upon the fire.

A support in the form of a flat strip 16, formed in the shape of a spiral, is wound around or attached to a vertical rod 17 and positioned in the chamber 11 beneath the acid container 6, as shown in Fig. 1. This spiral support is not attached to the chamber 11 but is removable therefrom for cleaning, etc., and the salt upon which the acid is to act is distributed over the surface of the same in sufficient quantity to generate the requisite amount of gas.

When it is desired to operate the fire extinguisher, the handle 3 is pulled up, raising the frame 5 carrying the acid container 6. This upward movement first causes the sharp pointed pins 10 to puncture the upper end of the acid container to form an air-vent, and when the upper wall or end of the container 6 reaches the shoulders on the

pins 10 the further upward movement of the frame 5 causes the knife edge 9 to puncture the lower wall or end 8 and then the inner wall 7. The knife 9 being tapered 5 forms a large opening in the lower wall 8 and the point thereof a smaller opening in the inner wall 7, the several parts then standing in the position shown in Fig. 2. As the handle 3 is now pushed downwardly 10 the acid in the lower portion of the container 6 is released at once while that in the upper portion continues to flow in a smaller amount over the salt on the spiral support 16. It will thus be seen that, on account of 15 the construction and arrangement just described, a large amount of acid will immediately flow over the relatively large surface of salt carried on the spiral support 16, causing a chemical action which immediately 20 produces a large volume of gas and the flow of acid being continued through the smaller opening in the inner wall 7 of the acid container 6 will continue the action and the production of gas, which passes out 25 from the gas chamber 11 through the valve 12 and forces the liquid in the container 1 through the pipes 13 and 14 in a continuous stream.

The gas generating chamber 11 may be 30 readily removed from the container 1 and the acid container 6 removed from the frame 5 for replacement. The spiral support 16— 17 is also removable for the purpose of cleaning, etc.

35 It will thus be seen that a simple device is provided by means of which the fire extinguisher becomes instantly operative when required, not only insuring the forcing out of the fire extinguishing liquid in a continuous stream but providing for the same being delivered at high pressure from the start. This feature is important in devices of this nature, in which the efficiency of the fire extinguisher in putting out the fire depends to a large degree upon the quickness with which the same may become operative.

As many changes could be made in the above construction and many apparently 50 widely different embodiments of my invention designed without departing from the scope of the appended claims, I intend that all matter contained in the above description or shown in the accompanying drawings shall be interpreted as illustrative merely of an operative embodiment of my invention and not in a limiting sense.

What I claim is:—

1. In a fire extinguisher, in combination, 60 a container for the fire extinguishing fluid, and gas generating means comprising an acid container and a spiral support upon which a salt is carried, said acid container being relatively mounted and maintained in position over the support while the acid is

being discharged therefrom, and means for liberating the acid from its container.

2. In a fire extinguisher, in combination, 70 a container for the fire extinguishing fluid, and gas generating means comprising an acid container and a vertically extending spiral support upon which a salt is carried, said acid container being mounted above the upper end of said support and maintained in said position while the acid is being discharged therefrom, and means for liberating the acid from its container. 75

3. In a fire extinguisher, in combination, 80 a container for the fire extinguishing fluid, and gas generating means comprising an acid container positioned in a chamber communicating with said first named container, and a spiral support also positioned in said chamber beneath said acid container said acid container being maintained in its position to cause the acid to flow over the support, and means for liberating the acid from its container. 85

4. In a fire extinguisher, in combination, 90 a container for the fire extinguishing fluid, and gas generating means comprising an acid container in two sections, a support upon which a salt is carried, said acid container being relatively positioned over said support, and means for liberating the acid 95 successively from the two sections of its container.

5. In a fire extinguisher, in combination, 100 a container for the fire extinguishing fluid, and gas generating means comprising an acid container in two sections, a support upon which a salt is carried, said acid container being relatively positioned over said support, and means for liberating the acid quickly from one of said sections of the acid 105 container and slowly from the other section.

6. In a fire extinguisher, in combination, 110 a container for the fire extinguishing fluid, and gas generating means comprising an acid container having a double bottom, a support upon which a salt is carried, said acid container being relatively positioned over said support, and means for puncturing 115 said double bottom.

7. In a fire extinguisher, in combination, 120 a container for the fire extinguishing fluid, and gas generating means comprising an acid container having a double bottom, a support upon which a salt is carried, said acid container being relatively positioned over said support, and means for puncturing 125 said double bottom with openings of different sizes.

8. In a fire extinguisher, in combination, 125 a container for the fire extinguishing fluid, and gas generating means comprising an acid container having a double bottom, a support upon which a salt is carried, said acid container being relatively positioned 130

over said support, and means for puncturing said double bottom with openings of different sizes successively.

9. In a fire extinguisher, in combination, a container for the fire extinguishing fluid, and gas generating means comprising an acid container having a plurality of sections, and an inclined support upon which a salt is carried, said acid container being relatively positioned and arranged over the support, and means for liberating the acid

from its container and for causing the same to flow from the several sections thereof at different rates over said salt support.

Signed at New York city, in the county 15 and State of New York, this 17th day of November, 1913.

LEWIS J. DOOLITTLE.
